SCREENING MEANS FOR VACUUM ELECTRIC
TUBE DEVICESJohn Mathieson Dodds, Timperley, and John
Heywood Ludlow, Bowdon, EnglandApplication December 29, 1943, Serial No. 516,107
In Great Britain May 13, 1938

3 Claims. (Cl. 250—40)

1

This invention relates to high power vacuum electric tube transmitter devices or valves of the kind which are operated in conjunction with appropriate circuits on very low wavelengths of the order of 50 metres and less and even below ten metres, and having wavelength changing arrangements involving the selective connection of different inductances.

The invention aims at providing very high efficiency screening between the anode and grid circuits of a high frequency transmitting valve.

According to the present invention the several inductance coils and the wavelength changing switches of the grid circuit of the valve or valves are located in a metal compartment or chamber and the switch blades are connected to the terminal (or terminals) of the control grid (or grids) of the valve (or valves) by conductors located in screening tubes or a single screening tube directly connecting said compartment or chamber and the terminal of the screening grids in the case of a valve in accordance with British Letters Patent No. 497,359 or with a relatively small screening chamber or box applied to a valve in accordance with British Letters Patent No. 414,753 which small chamber is of sufficient size only to shield the appropriate parts of the valve, with requisite clearance in relation to the voltage differences. It will be understood that the several inductance coils may be mounted on a panel or on pillars in the relatively large grid circuit chamber or compartment wherein also may be located the tuning condenser, if any, for said grid circuit inductance coils.

In applying the present invention to a valve in accordance with prior British Letters Patent No. 497,359 the screening box 30 shown in Figs. 2, 3 and 4 of specification of British Letters Patent No. 497,360 may be replaced by a metal tube or conduit the end of which fits directly against the side of the central metal envelope member 101 and contains the projecting control grid supporting leads 31 to which are attached the feeders which pass, in an extension of said conduit, to the selector switches in the manner hereinbefore indicated.

In carrying out the invention for a valve or a pair of valves of the kind indicated in Fig. 1 of British Letters Patent No. 497,360 aforesaid, the screening box may be of such minimum size that it contacts with the condenser 20 and/or 19 and covers the terminals 14 and 17, a pair of leads or at least the control grid lead being taken through a lateral aperture in said screening box and through the tubular conductor associated therewith to the blades of the inductance selector switch, which may be housed adjacent the group of inductances in another sub-compartment of the main cubicle.

To enable the present invention to be fully

2

understood it will now be described by way of example with reference to the accompanying diagrammatic drawings, in which:

Figure 1 is a sectional elevation illustrating the present invention and that of Ser. Nos. 516,103, and/or 516,105, applied to a valve which is per se in accordance with British Letters Patent No. 414,753 (aforesaid) and

Fig. 2 is a transverse section showing the present invention applied to the push-pull valve structure which is per se in accordance with British Letters Patent No. 497,359 aforesaid.

Referring to Fig. 1 of the accompanying drawings, the valve therein diagrammatically illustrated, in general comprises the anode 1 sealed to an insulating tube 2 which is connected to a pipe 3 which in turn is connected with an evacuating pump whereby the valve is continuously or intermittently evacuated during operation. At 4 is shown the filament cathode, at 5 the control grid and at 6 the screening grid. The screening grid 6 is formed with a conductive cap 6a so as to make the screening grid electrically continuous. Obviously there may be further grids such for instance as a suppressor grid between the screening grid 6 and the anode 1. Sealed to the top of the anode is an insulating tube 7 upon which is sealed a metal ring 8 which carries the tubular support 9 of the screening grid 6. Sealed to the metal ring 8 is an insulating ring 10 and sealed to the top of the latter is a metal ring 11 which carries a support 12, in the form of a half tube, for one end of the filament 4. Sealed above the ring 11 is a further insulating ring 13 upon which is sealed a metal ring 14 which carries the other filament support 15, also in the form of a half tube. Above the metal ring 14 is secured an insulating tube 16, the upper end of which is closed by a plate 17 which carries a tubular support 18 for the control grid 5. At 19 and 20 are shown respectively the screening grid bypass condenser and the filament bypass condenser which condensers are annular. The numeral 14a designates a connection between the filament terminal 14 and the screening box 21a. This direct connection serves to minimize the inductance of the cathode circuit.

At 21 is shown part of the screening box or subcompartment for the grid circuit inductances 22, 23 and 24, which have different values and are adapted to be selectively connected, in the example, by wavelength change switches 25 to the grids of a pair of push-pull valves, only one of which is illustrated in the figure. This connection is effected by conductors 26 centrally located in the metal tubes 27 which connect the compartment or chamber 21 with the relatively small box 21a for each of the two valves. Each box 21a houses and shields the appropriate terminals of the valve and in particular the grid terminal 17 thereof. The tuning or trimming condenser 28

for the inductances 22, 23 and 24 is shown located in the compartment or chamber 21, but it will be obvious that such condenser may be duplicated with one in each of the relatively small chambers 27a so as to tune the inductances with respect to the effective earth. It will be appreciated that with such an arrangement the screening between the control and anode electrodes is of a very high order since it is continuous both internally and externally of the valve.

It will be understood furthermore that the invention is not limited to push-pull valves since it may be applied to a single valve.

Referring to Fig. 2 of the accompanying drawings, this illustrates the invention applied to a push-pull valve in accordance with British Letters Patent No. 497,359 (aforesaid). Secured to the central metal member 101 of the valve is the tubular member 29 which fits around said central member and extends to an opening 30 in the control grid circuit screening compartment or chamber, part of which is indicated at 31, this chamber containing, as described with reference to Fig. 1, the grid tuning inductances (not shown) adapted to be selectively connected on the one hand by switch blades of which one is indicated at 32, mounted on a shaft 33 and carried by the right-hand ends of the straight bar or other conductors 34 which at their left-hand ends are secured to the terminal members 35 of the control grids of the valve. In the arrangement shown in Fig. 2 the tuning or trimming condenser for the grid inductance coils may be located in the compartment or chamber 31 or it may be provided, for example, between the leading-in members 35, as illustrated by way of example in Figs. 2 and 3 of the drawings of specification of British Letters Patent No. 497,360 (aforesaid).

We claim:

1. In a radio transmitter for high frequencies, a valve having a control grid and anode, a resonant circuit electrically connected with said control grid, a screening electrode separating the control grid and anode, a conductive support for said screening electrode forming an electrically continuous connection therewith, an electrical screening enclosing said resonant circuit, electrical screening enclosing the connection between the control grid and resonant circuit and forming a continuous electrical connection on the one side with the screening electrode support and on the other side with the resonant circuit screen, the arrangement being such as to form an electrically continuous screen between the control grid circuit and anode circuit both internally and externally of the valve.

2. In a radio transmitter for high frequencies, a valve having a control grid and anode, a resonant circuit, an electrical connection between said control grid and said resonant circuit, a tubular screening electrode closed at the anode end and separating the anode and control grids, a tubular support for said screening electrode, an annular terminal member connected to said electrode support, a terminal support for the control electrode located in the side of the screening electrode terminal remote from the anode, a screening box surrounding said control grid terminal, a high frequency electrically continuous connection between the screening box and the screening electrode terminals, a screening box surrounding the resonant circuit and screening surrounding the

connection between the control electrode and resonant circuit, said last mentioned screening forming an electrically continuous connection on the one side with the screening box of the control electrode and on the other side with the screening box of the resonant circuit, the arrangement being such that continuous electrical screening is formed between the control grid circuit and the anode circuit both internally and externally of the valve.

3. In a radio transmitter for high frequencies, a valve having a control grid and anode, a resonant circuit, an electrical connection between said control grid and said resonant circuit, a tubular screening electrode closed at the anode end and separating said anode and control grid, a tubular support for said screening electrode, an annular terminal member connected to said electrode support, a terminal support for the control electrode located on the side of the screening electrode terminal remote from the anode, a screening box surrounding said control grid terminal, an annular condenser surrounding said valve and having one condenser plate forming an electrically continuous connection with the screening box, an electrically continuous connection between a second plate of said condenser and said screen electrode support whereby said condenser acts as a high frequency bypass for the screening electrode and at the same time maintains continuity of the screening, filament terminal members located between the control grid terminal and the screen grid terminal, a direct electric connection between one of said filament terminals and said screening box, a screening box surrounding said resonant circuit and screening surrounding the electrical connection between the control grid and resonant circuit and forming electrically continuous connections on the one side with the control grid screening box and on the other side with the resonant circuit screening box, the arrangement being such that an electrically continuous screening is formed between the control grid circuit and the anode circuit both internally and externally of the valve.
